UNITED STATES PATENT OFFICE.

HENRI SANDOZ, OF TAVANNES, SWITZERLAND.

STEM WINDING AND SETTING MECHANISM.

SPECIFICATION forming part of Letters Patent No. 760,647, dated May 24, 1904.

Application filed October 2, 1903. Serial No. 175,484. (No model.)

To all whom it may concern:

Be it known that I, HENRI SANDOZ, a citizen of the Republic of Switzerland, and a resident of Tavannes, Switzerland, have invented 5
a new Winding and Setting Mechanism, of which the following is a specification.

One form of the winding and setting mechanism which constitutes the object of this invention is illustrated in the accompanying 10 drawings, given by way of example.

Figures 1 and 2 are elevations, and Fig. 3 a plan, of the winding and setting mechanism.

This mechanism has an extremely limited 15 number of parts. Its action is reliable and extremely simple.

A lever A, pivoting at *a*, has three effective ends, the one, *c*, engaging in the groove E of the winding-stem G, the second, in the form of a nose, being intended to act on the arm 20 B, and the third, M, being under the influence of a spring R, one end of which engages in the notch *r*, while the other end of this same spring lodges at *r'* against the arm B, which is pivoted at *b*, the said arm B engaging 25 in the groove S of the movable pinion D. The spring R thus tends at the same time to raise the stem G and the movable pinion D, so as to place it in contact with the wheel F.

The position of the parts shown in Fig. 1 is 30 that for setting the hour, the movable pinion being in contact with the motion-work wheel *d*. This position is insured by the nose C entering a recess *c* in the arm B. A bridge *p*, fixed by two screws *v v'* on the plate P, supports 35 the three different parts of the mechanism. If the stem G be pressed, the nose C

is moved back, Fig. 2, and no longer retains the arm B, which under the influence of the spring R brings the movable pinion into contact with the crown F, this being the winding-up position. 40

The stem G is most generally controlled by a "crown stem" which is adjusted in the pendant and known as "American stem."

The dimensions and to a certain extent the 45 forms of the parts of this mechanism may vary.

Having now described my invention, I claim as new and wish to secure by Letters Patent—

In winding and setting mechanism for watches, the combination with a plate of a 50 winding-stem having a groove E therein, and having also a reduced portion, a crown-wheel F on said reduced portion, a sleeve D slidably mounted on said reduced portion and having a groove S therein, a three-arm lever A pivoted to the plate and having one of its arms 55 engaging in the slot E, a second lever B engaging in the groove S and having a slot therein, said slot being in the axial line of the pivot of lever A, and a spring having one end 60 engaging with the lever B and its other end engaging with one arm of the three-arm lever A, the third arm of said lever being adapted to engage in the slot in the lever B when the hands are to be adjusted. 65

In witness whereof I have hereunto set my hand in presence of two witnesses.

HENRI SANDOZ.
